UNITED STATES PATENT OFFICE.

JOSEPH PRICE, OF NEW YORK, N. Y., ASSIGNOR TO THE GRISCOM-RUSSELL COMPANY, OF NEW YORK, N. Y., A CORPORATION OF DELAWARE.

EVAPORATOR.

Application filed June 12, 1923. Serial No. 644,971.

The present invention relates to evaporators of the type employed to produce purified boiler feed-water from water containing scale-forming impurities and has to do 5 primarily with the construction of the heating element and its assembly in the evaporator.

The heat for vaporizing the liquid in evaporators is usually derived from steam admitted to heat transferring coils or tubes arranged within the evaporator shell and extending into the liquid to be evaporated. In cases where the heating element is made up of straight tubes the tubes are 10 usually arranged in substantial parallelism to constitute a unitary bundle comprising tube sheets in the ends of the bundle. The tube ends are expanded or otherwise fixedly secured in the tube sheets. The tube bundle 15 is then submerged or partly submerged in the liquid within the shell and heating steam supplied to the tube bundle to maintain the liquid in a state of constant ebullition and thereby effect the desired evaporation. During 20 the vaporizing process a portion of the scale-forming impurities in the liquid precipitate out and to a certain extent collect on the surfaces of the heating tubes in the form of a hard scaly deposit. In the co-pending application, Serial No. 501,058, filed 25 Sept. 16, 1921, in the name of Russell C. Jones and assigned to the assignee of this application, there is shown an evaporator of this general type employing in its heating element tubes which are slightly bowed for 30 the purpose of cracking off and loosening accumulated scale. Upon changes in temperature these bowed tubes will flex and in this manner crack and loosen the scaly deposit 35 which has been precipitated on them. The present invention is conceived particularly as an improvement over the type of apparatus disclosed in the above mentioned co-pending application, but it is applicable 40 not only to an apparatus embodying a heating element employing bowed tubes, but is applicable as well to any apparatus having a heating element which consists of a bundle 45 of closely grouped tubes which in the course of operation are likely to require cleaning or otherwise need attention.

Evaporators employing a heating element consisting of a large number of closely grouped tubes are open to the objection that 50 the tubes of the bundle are relatively inac-

cessible for purposes of cleaning or repair. In evaporators employing a tube bundle consisting of straight tubes circular in cross section scale accumulates rapidly and frequent removal of this scale is required. Due to 60 temperature changes the tubes exert a slight cracking action on the scale due to a difference between the temperature coefficient of the metal of the tubes and that of the scale deposit, but this action is entirely insufficient to maintain the tubes free from 65 scale. Even with bowed tubes it may be necessary to obtain access to the tubes of the heating element for the purpose of repairing a damaged tube or for the purpose of 70 removing scale deposits which have been permitted to accumulate through inattention of the operator to the automatic sealing of the heating element. I have found that it is not advisable to remove the entire heating element as a unit, due primarily to the 75 fact that a heating element of this type is extremely difficult to handle without danger of injury. To obtain access to the tubes the operator must enter the shell, and his difficulty in getting at the heating surfaces is 80 readily apparent. Even if the entire bundle were withdrawn from the shell the inner tubes of the bundle would, nevertheless, be 85 difficult of access.

It is a principal object of this invention to provide an apparatus employing a tube bundle consisting of a plurality of closely grouped tubes arranged in substantial parallelism, of such construction that the heating element is readily removable from the shell and easy access is provided to every tube of the bundle.

It is also an object to provide an evaporator wherein bowed tubes or tubes otherwise deformed for facilitating scale removal may be employed and may be grouped into a compact tube bundle which permits of ready removal and at the same time provides for easy access to each tube of the heating element.

The present invention contemplates an apparatus employing a tube bundle built in sections. The bundle consists of a number of closely grouped substantially parallel tubes having their ends securely supported in suitable tube sheets, which tube sheets are maintained rigidly spaced in case a bowed tube construction for scale removal is desired. When assembled in the shell the heat-

ing element is substantially the same in all respects as a unitary tube bundle of this type. Likewise the entire apparatus presents substantially the same appearance as the ordinary evaporator of this type and is identical in operation.

In carrying out my invention I preferably construct the tube sheets in sections, each section supporting one or more rows of tubes 10 extending across the tube bundle. A corresponding tube sheet section is provided at the opposite end of the apparatus, so that the two sections with the tubes which they support constitute a removable element 15 which may be withdrawn bodily from the evaporator shell. I prefer to employ one or two rows of tubes in each section of the heating element for the reason that with this construction every tube will be readily accessible 20 when the heating element section is removed from the shell. Each removable unit is relatively light in weight and is easy to handle without danger of bending or otherwise injuring the heating tubes. The 25 individual sections of the heating element are assembled in such fashion that any one or more of the sections may be withdrawn from the shell at one time.

I have illustrated a preferred embodiment 30 of my invention in the accompanying drawings, wherein—

Fig. 1 is a sectional elevational view illustrating an apparatus embodying my invention;

Fig. 2 is a transverse sectional view taken centrally of the apparatus;

Fig. 3 is a front elevational view with the cover of the apparatus removed, showing the heating element in position;

Fig. 4 is a similar view taken from the back of the apparatus;

Figs. 5 and 6 are a partial sectional view and a front elevational view respectively of one section of the heating element;

Figs. 7 and 8 are partial views showing the construction of the inlet and discharge manifolds;

Figs. 9 and 10 are views similar respectively to Figs. 5 and 6 showing the rear end 50 of a section of the heating element; and

Fig. 11 is an end view of a section of the heating element illustrating a modified construction.

Referring to the drawings, 1 indicates the containing shell of the evaporator and 55 2 indicates the bundle of heating tubes disposed within the shell. Steam is supplied to the tubes 2 through a suitable inlet opening 3 and after being condensed in its passage through the tubes 2 is returned 60 through a drain line 4 and discharged at the outlet 5 provided for the purpose. The vapor generated in the evaporator shell proceeds upward through the baffle plates 6 and separator 7 and is passed out of the

apparatus through the opening 8. A trough-shaped baffle 9 is preferably provided to cover the upper portion of the tube bundle and extend down beneath the surface of the liquid at the sides of the 70 bundle as indicated in Figure 2 for the purpose of minimizing the agitation of the liquid in the shell produced by ebullition. The shell 1 is provided with a removable cover 10 which affords access to the interior 75 of the apparatus.

The tubes 2 of the heating element may be straight tubes of circular cross section or they may be deformed in such fashion that their surfaces will flex upon the changes in 80 temperature to thereby remove accumulated scale. I have here shown the tubes slightly bowed so that the middle portion of each tube is displaced a short distance out of a straight line connecting its ends. The 85 ends of the tubes are fixedly supported in suitable tube sheets 11 and these tube sheets are maintained against relative displacement by stayrods 12 at the top of the tube bundle and by the tube 4 at the bottom of 90 the bundle which serves as a stay-tube as well as a discharge passage for the condensate. Upon increase in temperature, therefore, longitudinal expansion of the tubes 2 will produce a flexure of the tubes and the 95 extent to which the tubes are bowed will vary depending upon their temperature. By successively introducing into the tubes a quantity of hot steam and a quantity of 100 cold water a marked flexure of the tube surfaces is obtained and a correspondingly effective exfoliation of the accumulated scale accomplished.

The tube bundle constituting the heating element of the apparatus is built in sections. 105 I have here illustrated each section of the heating element as comprising two vertical rows of tubes extending across the height of the tube bundle. Each of these sections is a complete unit in itself and receives its 110 quota of heating steam, condenses the steam during its passage along the length of the apparatus, and is provided with its individual return tube 4 for conveying the condensate back to the discharge outlet. The 115 construction of the improved tube bundle sections is particularly shown in Figs. 5 and 6. The front end of the section comprises a chamber 13 for receiving the heating steam. This chamber is directly in 120 communication with the inlet ends of the tubes 2 and thus serves to supply the tubes constituting this particular section. The outlet ends of the tubes of the section discharge into a chamber 14 (Fig. 9) provided at the rear of the tube bundle section. The chamber 14 is also in communication with the inlet end of the drain tube 4 and serves to receive the condensate issuing from the tubes 2 and to pass it along into the tube 4, 130

whence it is again conveyed down the length of the apparatus and emptied into the discharge chamber 15 (Fig. 5) which is provided in the front end of the tube bundle 5 section.

For the purpose of affording access to the tube ends holes are made in the outer walls of each header in register with the respective tubes of the bundle. A tool for affixing the tubes in the tube sheet may be inserted through these holes and likewise a cleaning tool may be introduced to remove deposits from the interior of the tubes. Each hole is tapped and is provided with a suitable plug 23 to render the chamber liquid tight during operation of the apparatus.

From the showing in Fig. 1 it will be noted that when the tube bundle sections are assembled in the shell the appearance of the heating element is not essentially different from that of a heating element of this type constructed as a unitary bundle. Likewise the operation and attention required are in all respects similar to that of the usual evaporator of this type. Each of the individual tube bundle sections slides on a track 16, as best shown in Figs. 2 and 10. These tracks are here shown as angle 20 irons extending longitudinally of the evaporator shell and spaced to support the individual tube bundle sections in proper relative position.

At the front end of the tube bundle an inlet manifold 17 extends transversely of the shell and serves to supply the sections of the tube bundle with heating steam. The manifold is rigidly associated with the apparatus shell, and each of the individual tube bundle sections is bolted to it for support, as indicated at 18. When thus secured in position the inlet openings in the respective tube bundle sections lie in register with the corresponding openings 19 provided on the inlet manifold. In order to further secure the individual tube bundle sections, and to maintain them in fixed relation, provision is made for inserting a long bolt 20 between adjacent sections, which bolt carries a dog or bracket 21, designed to bridge over on to adjacent sections and thus lend rigidity to the structure. Similarly, at the lower side of the tube bundle sections a discharge manifold 22 is provided and facilities are furnished for attachment to this manifold in the same manner as attachment to the upper manifold is accomplished.

To remove the individual sections of the heating element from the shell it is merely necessary to remove the bolts serving to support it and then withdraw the section bodily through the open end of the shell. Any desired one of the tube bundle sections may be withdrawn or any number of them 60 may be positioned at the exterior of the

shell at one time. It is thus evident that complete and ready access to any cube of the bundle is possible. Individual sections employing two rows of tubes as above described permit of ready access to each tube, 70 but if desired these sections may consist of only one row of tubes, as shown in Fig. 11. Similarly, any desired number of rows of tubes may be included in each section. I prefer to have each section extend vertically 75 of the bundle as shown, although it would be possible to arrange each tube section to include a horizontal row of tubes if desired. The vertical arrangement is preferred, however, due to ease of removal and 80 general convenience in handling.

While I have illustrated a preferred embodiment of my invention, it is to be understood that certain changes and modifications may be made within the scope of the appended claims.

I claim:

1. An evaporator for producing purified vapor from liquid containing scale-forming impurities comprising a shell for containing the liquid, a heating element consisting of a plurality of independently removable sections, each of said sections comprising headers at the respective ends thereof, a plurality of slightly bowed heat transferring tubes 90 extending between said headers, and means forming a part of each section for spacing the respective headers a fixed distance from one another irrespective of expansion and contraction of said tubes, the extent of the 100 bowing of said tubes away from a straight axial line being sufficient to prevent rupture under expansion and contraction but not sufficient to prevent a substantial exfoliation 105 of the scaly deposit of impurities accumulated on the tubes by bending or straightening of the tubes under change in temperature.

2. In an apparatus for heating and treating water involving the deposit of scale-forming substances from the water, the combination of a vessel, a heating element therein consisting of a plurality of independently removable sections, each of said sections comprising a plurality of heat 110 transferring tubes arranged in substantial parallelism, tube sheets supporting the ends of said tubes, said tubes and tube sheets being removable as a unit from the vessel 115 independently of the remaining sections of the heating element, a tie-bolt extending between the upper portions of the respective tube sheets and a drain tube of substantial dimensions extending between the lower portions of the tube sheets, said tie-bolt and drain tube maintaining the tube sheets against free relative movement under the expansion and contraction of the heating tubes, said heating tubes being bowed 120 away from a straight axial line sufficiently 125 130

to prevent rupture but not sufficiently to prevent a substantial exfoliation of the scaly deposit of impurities accumulated on the tubes by bending or straightening of the tubes under change in temperature.

3. In an evaporator, the combination of a shell for the liquid to be evaporated having a detachable portion at one end to give access to its interior, a heating element consisting of a plurality of independently removable sections each section comprising a pair of tube sheets having a plurality of heating tubes extending therebetween, said tubes being arranged in substantial parallelism along their entire length, and means forming a part of each of said removable sections for maintaining said tube sheets against free relative movement under the expansion and contraction of said tubes, said tubes being bowed away from a straight axial line sufficiently to prevent rupture but not sufficiently to prevent a substantial exfoliation of the scaly deposit of impurities accumulated on the tubes by bending or straightening of the tubes under change in temperature.

4. In an apparatus for heating and treating liquids involving the deposit of scale-forming materials, the combination of a vessel, a removable heating element therein consisting of a plurality of independently removable sections each comprising a pair of tube sheets having heat transferring tubes extending therebetween and arranged in substantial parallelism, said tubes being slightly offset at their middle portions, the extent of such offset being just sufficient for elongation of the tubes through heat expansion to produce a further bowing of the tube instead of rupture, and means forming a part of each removable section for holding said tube sheets against the thrust occasioned by the elongation of said tubes.

5. In an evaporator, the combination of a shell for the liquid to be evaporated having a detachable portion at one end to give access to the interior, a heating unit within said shell consisting of a plurality of heat transferring elements constituting separate independently removable sections of the said heating unit, each of said separate sections being slidable horizontally to and from its operative position within the shell, and each having a header provided with vertical joint faces having openings for re-

ceiving and discharging working fluid, inlet and discharge manifolds provided on said shell having a plurality of openings spaced to correspond with the positioning of said respective independently removable heat transferring sections, said manifolds having vertical joint faces positioned to contact with the joint faces of the several sections and serving as stops to arrest the movement of said sections in their operative position as they are slid into said shell, and means for maintaining said coacting joint faces in fluid-tight relation.

6. In an evaporator, the combination of a shell for the liquid to be evaporated having a detachable portion at one end to give access to its interior, a heating unit consisting of a plurality of independently removable sections, each of said sections comprising a plurality of heating tubes positioned in substantial parallelism, tube sheets in which the opposite ends of the tubes are supported, a header associated with the front tube sheet having inlet and outlet joint surfaces at right angles to the axis of the heating section, said inlet communicating with a large portion of the tubes of the section and said outlet communicating with those tubes not in communication with said inlet, and a chamber at the other end of the removable heating section in communication with all of said tubes, an intake passage provided on said shell for conveying heating fluid to the apparatus, a discharge passage on the shell for receiving fluid discharged from the apparatus, intake and discharge manifolds secured to the interior of the shell and in communication respectively with said intake and discharge passages, a plurality of rails within the shell upon which each of said independently removable sections respectively is slidable to and from its operative position, said manifolds having joint surfaces positioned in horizontal alignment with the joint surfaces on the heating section headers when said sections are supported on said rails, and the planes of the joint surfaces of said manifolds being disposed so as to contact with the joint surfaces of the headers when the heating sections are slid into their operative positions within the shell.

In testimony whereof I affix my signature,

JOSEPH PRICE.
